UNITED STATES PATENT OFFICE.

GEORGE H. DAWSON, OF BOSTON, MASSACHUSETTS, ASSIGNOR TO SERVICE BUREAU,
INC., OF CAMBRIDGE, MASSACHUSETTS, A CORPORATION OF MASSACHUSETTS.

INDEX TAB.

Application filed July 26, 1926. Serial No. 124,886.

This invention relates to index cards and particularly to an improved type of tab or label holder for guide or spacing cards adapted for use in a so-called vertical filing system to separate groups of index cards, folders, files or the like.

The objects of the invention are to produce a tab of transparent sheet material having an outer reinforcing strip, the transparent portion of the tab providing a window on opposite sides of the card and the metal strip providing increased rigidity at a position which will not increase the bulk of the index system, and in general to provide an improved tab which is economical and easy to manufacture and is durable, moisture proof and wear-resisting in use.

Preferred embodiments of the invention are illustrated in the accompanying drawings, in which

Fig. 1 is a front elevation of a card having the improved tab;

Fig. 2 is a rear view of Fig. 1 showing the manner of inserting a label within the tab;

Fig. 3 is a fragmentary elevation showing an optional construction of a card prior to the attachment of a modified type of tab; and

Fig. 4 is an enlarged vertical section on the line 4—4 of Fig. 1.

The card body 5 may be made of any preferred sheet of material, such as heavy paper, cardboard or fibreboard, and has at its upper margin a pair of integral, spaced-apart tongues 6 projecting at right angles thereto. The opposed inner edges of the tongues are preferably extended into the card body to define the margins of a relatively deep recess having a horizontal bottom edge 8; but, as indicated in the optional construction shown in Fig. 3, the recess provided by the tongues may extend only to the normal upper margin of the card. In either case the recess provides, in combination with the tab elements to be described, a pocket for a label or index slip 9, the pocket illustrated in Figs. 1, 2 and 4 permitting insertion of a larger label than in the construction shown in Fig. 3.

A pair of similar cover elements 10 and 11 of transparent sheet celluloid, either separate or integrally connected, are adhesively secured, by cement or other suitable fastening means, upon the front and rear sur-

faces, respectively, of card 5, covering the faces of the tongues 6 and extending downwardly over the card body. The outer edges of the celluloid sheets register with the outer shoulders of the card tongues so that the tongues and celluloid tab afford mutual strength and protection to one another. One of said sheets, for example rear sheet 11, is slit at 12, adjacent the bottom edge 8 of the card recess to permit the insertion of label 9 in the manner shown in Fig. 2. Slit 12 may be widened intermediate its ends to form opposed recesses 13 and 14, and the card body may have a recess 15 corresponding to the recess 14, to permit the insertion of a finger for the purpose of more readily grasping and withdrawing the label.

A reinforcing flange or bridge 16, consisting of a relatively narrow folded strip of metal or other suitable material is attached over the upper margin of the celluloid sheets, the ends of the strip being secured to the tab as by rivets 17 passing through these sheets and through tongues 6. In order that the upper edge of the tab may present a smooth surface, it is preferred that the length of the flange 16 be restricted at the fold so that the ends of the fold line will fit within opposed notches 18 provided at the respective tongue tips.

As thus enclosed by the celluloid sheets and reinforcing flange, the recess between the card tongues furnishes an unusually large label-receiving pocket, which is both dirt and moisture proof and which permits visibility of the label from either side of the index card.

Such construction permits the guide card to be used in different locations in the filing system by reversing the card so that the tab may appear either at the left or right hand side of the file drawer. For example, it may be preferred to locate the tab on each succeeding guide card in five different positions, respectively, each successive tab being offset to the right or left of the preceding tab, to permit visibility of the index data on each of the five guides from the front of the filing drawer or tray. The reversible feature of a tab having windows on either side, permits a single guide card to be used in either the first and fifth, or the second and fourth position; thus effecting a substantial saving in the different cutting and stamping operations employed in man-

ufacturing a set of guide cards for a filing system of the aforesaid type.

If it is preferred however, that but one side of the label be visible, it is obvious that either the perforate or imperforate cover sheet may be made of opaque material, or that a paper lining may be inserted between one of the cover sheets and the card surface to obscure the indicia on either side thereof, as desirable. Additional changes in structural details may also be incorporated in an index card or tab without departing from the spirit of the invention as defined in the appended claims.

An index device constructed in accordance with this invention provides a durable and handy tab having a rigidly reinforced outer edge which does not increase the bulk of the filing system in which the card may be utilized. Since the amount of metal necessary for the reinforcing flange is relatively small, the tab may be economically constructed without sacrifice of strength and serviceability in use.

I claim:

1. An index comprising a card provided with upstanding tongues forming a label-receiving recess between them, cover sheets

of non-metallic material secured to opposite surfaces of the card over said recess, and a channeled bridge piece attached to the ends of the tongues and spanning the recess, one of said cover sheets having a slit to permit the insertion of a label into said recess, and one of the cover sheets having a window permitting visibility of the label.

2. An index comprising a card provided with upstanding tongues defining a recess open at the top between their inner edges and having outer shoulders, cover sheets of transparent material secured to opposite surfaces of the card over said recess, and a metal flange folded over the upper edge of said cover sheets and said tongues to provide a label-receiving pocket within said recess, said flange terminating at the outer shoulders of the respective tongues and the ends of the flange being fastened to the ends of the tongues, one of said cover sheets having a horizontal slit at the bottom of said pocket to permit the insertion of a label therein, so that the upper edge of the label may be received within the folded flange.

Signed by me at Cambridge, Massachusetts, this 21st day of July, 1926.

GEORGE H. DAWSON.
